[57] CLAIM

The ornamental design for a bottle, as shown and described.

DESCRIPTION

FIG. 1 is a front and left side perspective view of a bottle showing my new design;

FIG. 2 is a rear elevation, the front elevation is a mirror image of the rear elevation except for the conventional screw threading on the bottle neck;

FIG. 3 is a top plan view thereof;

FIG. 4 is a bottom plan view thereof;

FIG. 5 is a left side elevational view thereof;

FIG. 6 is a right side elevational view thereof; and,

FIG. 7 is a perspective view of the bottle in a transparent embodiment.

The broken line showing of a bottle cap is for illustrative purposes only and does not form part of the claimed design. The other views of the second embodiment of the bottle are the same as the first embodiment except that the bottle is transparent.
